UNITED STATES PATENT OFFICE.

CARL HAFFNER, OF BROOKLYN, NEW YORK.

SHEET-PILE ATTACHMENT FOR PRINTING-PRESSES.

SPECIFICATION forming part of Letters Patent No. 372,410, dated November 1, 1887.

Application filed February 16, 1885. Renewed September 14, 1887. Serial No. 249,688. (No model.)

To all whom it may concern:

Be it known that I, CARL HAFFNER, of Brooklyn, in the county of Kings and State of New York, have invented certain new and 5 useful Improvements in Sheet-Piling Attachments for Printing-Presses, of which the following is a specification.

This invention has reference to an improved sheet-piling attachment for the fly-table of 10 printing-presses, whereby the sheets delivered by the fly are piled up regularly without requiring the attendance of a fly-boy.

The invention consists of a sheet-piling attachment for the fly-tables of printing-presses, 15 which is composed of a wing shaped upper part and an open framed lower weighted part, said attachment being hinged to the edge of the fly-table, as will appear more fully hereinafter and finally be pointed out in the claim.

20 In the accompanying drawings, Figure 1 represents a side elevation of the rear end of a printing-press, showing my improved sheet-piling attachment arranged at the fly-table of the press. Figs. 2 and 3 show side and end elevations of my improved piling attachment, 25 drawn on a larger scale. Fig. 4 is an end view of the fly-table with my improved attachment.

Similar letters of reference indicate corresponding parts.

30 A in the drawings represents the fly-table of a printing-press, to the rear edge of which is applied the sheet-piling attachment B, that is made of a wing-shaped upper part, b, of thin sheet metal, that extends above the fly-table A, 35 and of a lower weighted part, d. The wing-shaped part b is hinged to the edge of the fly-table or below the same, the lower weighted part being formed of a wire frame, as shown in Figs. 2 and 3, that is provided with eyes d' 40 d' for the pintle e of the attachment.

When the front and side gages, f, have been placed in proper position on the fly-table and

the printing-press is started, the fly delivers the sheets onto the fly-table, which are then regularly set up by the piling attachment. The 45 draft exerted by the air on the upper wing-shaped end of the piling attachment throws the same in backward direction against the action of its weight, while the latter returns the wing-shaped upper part and moves thereby 50 the sheet forward by the oscillating motions imparted to the attachment. As one sheet after another is delivered on the fly-table the piling attachment arranges them in connection with the gages in a reliable and uniform manner. 55

I do not claim the combination, with a receiving-table provided with gages and a fly sheet-delivery, of an evener or straightening device hung at the outer edge of the table, capable of outward movement by the blasts of air produced by the fly and adapted in its return movement to push inward the newly-delivered sheet against the gages. Nor do I claim the combination, with a receiving-table 60 having gages and a fly, of an evener or straightening device made heavier at its lower portion and hung to the outer edge of the table. 65

Having thus described my invention, I claim as new and desire to secure by Letters Patent— 70

A sheet-piling attachment for the fly-tables of printing-presses, composed of a wing shaped upper part and an open framed weighted lower part, and a hinge for connecting the attachment to the edge of the table, substantially as 75 set forth.

In testimony that I claim the foregoing as my invention I have signed my name in presence of two subscribing witnesses.

CARL HAFFNER.
